CONTRACTION JOINT

Original Filed Oct. 19, 1925

Robert C. Fischer
Inventor

UNITED STATES PATENT OFFICE

ALBERT C. FISCHER, OF CHICAGO, ILLINOIS, ASSIGNOR TO THE PHILIP CAREY MANUFACTURING COMPANY, A CORPORATION OF OHIO

CONTRACTION JOINT

Application filed October 19, 1925, Serial No. 63,361. Renewed November 26, 1929.

This application contains subject matter disclosed but not claimed in my Patent No. 1,655,835, dated January 10, 1928, which bears the filing date January 3, 1922.

5 My invention relates to a separating plate, various forms of which may be employed. The part that is new and distinct from anything shown in the previous art is that the plate is in one continuous piece, consisting of 10 metal, preferably having upper and lower flanges, held apart by a grooved central portion, which may be in the shape of an arc, a triangle, the right hand portion of an octagon, which would consist of the three lines 15 forming the right hand side, or may be square in shape, the first three designs being preferable.

20 My invention relates primarily to single course pavements and permits a double strength single tongue and groove, whereas a corrugated arrangement would divide the strength by oppositely protruding tongues and oppositely receiving grooves, thus weakening the structure thru the employment of 25 curved lines instead of sharp angles, as disclosed in my invention, which also enables the tongue to be formed in one piece, making for a stronger tongue, said arrangement enabling slabs to set more squarely together than the 30 prior art.

My invention in addition thereto provides for waterproofing between the faces of slabs, and in addition provides for expansion and contraction, which is an important feature, 35 and which has not been known in the prior art.

This design and style of contraction plate brings the flanges directly opposite each other, and the center arc, triangle or octagon 40 depression thru the plate, supports these flanges in vertical position, both upwardly and downwardly, allowing them to act as straight separating plates, while the center functions as a groove, and when the concrete is poured against the plate there is no 45

interference with the flow of the concrete, so that the concrete on one side forms a slab with an upper and lower straight face, and an intermediate section forming a tongue; while the slab on the other side has an upper 50 and lower straight face with a groove in its intermediate portion which receives the tongue.

This type of construction simplifies the art, in that less metal is used than where it is necessary to form an interlocking arrangement on a double section of pavement, where a corrugation or double lock is provided, which does not provide as strong a tongue and 55 groove arrangement as disclosed in my invention.

It also simplifies the prior art where a wood base or metal top is used, as the wood must first be moulded to shape and grooved to receive the metal, whereas in my invention it is 60 only necessary to press a single plate in one direction to obtain the desired result.

My invention relates primarily to staking in the ground, and the openings may be placed on the upper and lower side of the intermediate section forming the groove, enabling the stake to be placed therethru, holding the plate in a vertical position. Where a double tongue and groove arrangement is provided this cannot be effected, because the vertical 70 flanges interfere with any arrangement of this kind, unless the plate would be so devised as to have one vertical face staggered over the other vertical face, or unless other means were employed which would destroy the plate. 75 The plate, according to my invention, is staked in the ground previous to pouring the concrete against it.

The primary feature in my invention is to obtain a separating plate which will accomplish a single tongue and groove construction with an absolutely square setting together of the slabs, in order to make a better joint and also minimize the tendency of 80 85 90

one slab to pull away and separate from the other.

Likewise, because of the depth of the pavement, my invention is particularly adapted to 5 single course concrete and enables the slabs to form with a heavier and stronger single tongue and groove. Also, should it be desirable to prevent rusting, while at the same time utilizing the separating plate for thus 10 forming a tongue and groove joint in the slab, I prefer to use a waterproof paint which will withstand corrosion as nearly as possible, in order to preserve the plate; and so another 15 form of my invention is that of providing a protecting coat of paint for the metal, in order to preserve it from corrosion.

Still another form of my invention is that 20 of providing for a minimum of expansion and contraction, and for this purpose I coat the plate or contraction joint with bituminous material, either fibrated or otherwise, this making it heavier and allowing it to act both as a separating and forming plate of 25 single tongue and groove slabs, and at the same time providing a compressible material which will take up the expansion and contraction and aid in the waterproofing of the 30 space between the slabs.

The single tongue and groove design 35 permits of the shaping of the material more readily than a corrugated or any other design, and will not be distorted out of shape as readily. A multiplicity of curves will mean multiplicity of deflections in the material, thus destroying the shape of the slab and weakening the tongue and groove hold.

I do not wish to be limited to the reinforcing material which supports the compressible material, nor to the material out 40 of which the separating plate is prepared.

The expansion material may consist, first- 45 ly, of an asphaltic mass formed into a premoulded expansion material, secondly, it may consist of an asphaltic mass having mixed with said mass fibrous material to reinforce the asphaltic mass, in proportions adequate 50 so that the proportion of asphalt will exceed the proportion of fibre, said mass being formed into a premoulded expansion material.

Where the plate is immersed into bituminous material it is preferred that a blown 55 bituminous material be employed, because of its better resistance to temperature changes.

Where the plate is immersed in an asphaltic fibrous mixture the fibre content 60 should not exceed more than ten per cent, in order to retain the asphaltic mass in a liquid condition, as too much fibre would stiffen the mass so that immersion would be impractical. Likewise asphaltic material may be placed on either side of the plate and suitable rolls provided which will enable the as-

phalt to be pressed as a facing on the plate for the purpose described.

This single tongue and groove division plate need not come to the surface of the concrete, but may stop within an inch or so 70 of the surface and concrete placed thereover, or the concrete may be suitably edged to the plate, as desired.

In the accompanying drawing the figure 75 is a view in section illustrating my improved joint.

Referring to the drawing in detail a supporting section —*b*— with flanges, —*cc*— coated with a compressible bituminous material —*aa*—.

It can readily be understood that the process of manufacture is simply one of forming metal, fibre, or compressible expansion material or a combination of the metal with the expansion material, or the fibre with the 85 expansion material, either by adhering one to the other, coating one with the other, pressing the reinforcing sheet with the expansion material, or utilizing the expansion material independently.

Any suitable method may be utilized for 90 painting the single tongue and groove plate, or bituminous material may be coated over the separating plate by immersion in a bituminous material, or the bituminous fibrated 95 material may be poured over the separating plate, or suitable expansion material may be prepared and itself prepared into a separating 100 plate or cemented on a separating plate.

I claim:

1. An expansion joint comprising a strip 100 of bituminous material having upper and lower flat portions yoked together by an intermediate tongue and groove portion and internally reinforced by a strip of sheet metal 105 conforming to the configuration of the strip.

2. An expansion joint comprising a sheet metal strip having upper and lower flat portions yoked together by an intermediate tongue and groove portion and enveloped in 110 a bituminous jacket.

3. An expansion joint having upper and lower flat portions yoked together by an intermediate tongue and groove portion, said joint embodying in its construction a strip 115 cut from sheet metal and enveloped by plastic material having the inherent qualities of compressibility and expansibility, said metal strip being cut to conform to the configuration of the joint, and the plastic material being also formed to conform to the configuration of the joint.

4. An expansion joint comprising a sheet metal strip having upper and lower flat portions yoked together by an intermediate 125 tongue and groove portion, and enveloped in a bituminous jacket, said bituminous jacket having fibre distributed therethru.

5. An expansion joint comprising a re- 130 enforcing core having an intermediate tongue

and groove portion, and a covering of waterproofing material surrounding the core.

5 6. An expansion joint comprising a re-enforcing core having upper and lower flat portions yoked together by an intermediate tongue and groove portion, and a covering of waterproofing material surrounding the core.

10 7. An expansion joint comprising a re-enforcing core having upper and lower flat portions yoked together by an intermediate tongue and groove portion, and a covering of waterproofing material surrounding and conforming to the contour of the core.

15 Signed at Chicago, Illinois, this 13th day of October, 1925.

ALBERT C. FISCHER.
